UNITED STATES PATENT OFFICE.

ARTHUR B. LATHAN, OF ALBIA, IOWA.

TRACTION-ENGINE BRAKE.

No. 849,000.

Specification of Letters Patent.

Patented April 2, 1907.

Application filed June 8, 1906. Serial No. 320,893.

To all whom it may concern:

Be it known that I, ARTHUR B. LATHAN, a citizen of the United States, residing at Albion, in the county of Monroe, State of Iowa, have invented certain new and useful Improvements in Traction-Engine Brakes; and I do hereby declare the following to be a full, clear, and exact description of the invention, such as will enable others skilled in the art to which it appertains to make and use the same.

This invention has relation to brakes for traction-engines and for separators and threshing-machines driven by them.

It is well understood by those acquainted with threshing by machinery that it is difficult in moving the engine from place to place to control its speed at times with requisite readiness, for the reason, among others, that the person whose duty it is to look after the 15 brake has other matters to attend to, and in going over uneven roads and down steep grades it is often necessary that the brake should be applied with force and prompt energy when the brakeman's other duties take 20 his attention to such a degree or extent that he cannot reach or apply power to the brakes in proper time and with requisite force. I have conceived the idea of employing a brake mechanism for the purpose mentioned which 25 will permit the person in charge of the brake to control it with ease and readiness, so that other duties attendant upon getting the engine over the road can be looked after without interfering with attendance upon the 30 brake.

I will first proceed to describe the invention in view of the annexed drawings, forming a part of this specification, and then point out the part or improvement with particularity in the subjoined claim.

Of the said drawings, Figure 1 is a side view of so much of a traction-engine as it is necessary to illustrate in order to explain the invention. Fig. 2 is a sectional detail view 45 of the power-cylinder and its connection with the brake-band.

In the drawings, 10 designates the band-wheel on the axle of the ground-wheel 11. Surrounding the band-wheel is a strap 12, 50 embracing its rim 13, or it may be a special part thereon, which strap is adapted to grip

the rim by tightening it thereon through the medium of the tightening means of a form and construction to be presently explained.

14 is a vertically-arranged steam-cylinder, 55 preferably located above the band-wheel 10 and provided with a piston 15. The said cylinder is furthermore provided with a steam-inlet below the piston, with which inlet there is connected a steam-conduit communicating with the boiler or other source of steam-supply. A piston-rod 16 is connected at its upper end with the bottom of the piston and at its lower end with the convergent 60 ends of two links 17 and 18, the opposite ends of which links are connected to the separated ends of the band-tightening strap.

It will now be seen that when steam is admitted into the cylinder below the piston the latter will be forced up, and the piston-rod, 70 drawing upon the links 17 and 18, will tend toward bringing them into parallelism, and so tightening the strap on its rim, with the effect of stopping or impeding the rotation of the said wheel.

The throttles for operating the valves to admit steam to the cylinder will be conveniently located, so that the attendant can easily reach and operate them while attending to other duties arising out of exigencies in 80 getting the engine over difficult places.

It is to be particularly noted that the means for applying and regulating the brake, that has heretofore been a matter requiring much time and energy of the attendant, with 85 my invention is greatly simplified and can be actuated with all needed energy without calling for the exclusive time and efforts of the attendant, a matter of supreme importance in this class of improvements.

What is claimed as the invention is—

In a traction-engine of the class described, the combination of the ground-wheel and its axle, with the band-wheel secured on the axle of the ground-wheel, the band or strap 95 on the rim of the band-wheel having divided ends, a steam-cylinder located directly above the band-wheel, a piston in the cylinder, a piston-rod connected at its upper end with the bottom of the piston, the lower end of the 100 piston-rod being pivoted to the convergent ends of two links, the other ends of which are

connected to the divided ends of said strap, a steam-inlet to the cylinder below the piston, a steam - conduit communicating between said inlet and the boiler, and means, conveniently located, for controlling the admission of steam to, or shutting it off, from the cylinder.

In testimony whereof I affix my signature in presence of two witnesses.

ARTHUR B. LATHAN.
